UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR AN ANDIRON.

SPECIFICATION forming part of Design No. 36,049, dated September 9, 1902.

Application filed July 29, 1902. Serial No. 117,569. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Andirons, of which the following is a full, clear, and exact description, reference being had to the accompanying drawing, forming part hereof, in which is represented a pair of andirons duplicates of each other and each embodying the design.

The leading features of the design consist of a central upright or standard with a bust-figure at the top, having extending from its sides and shoulders wing-like formations, nearly meeting at their upper ends above the head of the figure in a spherical body, having the representation of a torch-flame extending

from its top. Below the bust-figure is a fluted body portion ending at each side in scroll-like feet resembling somewhat in shape the letter C. The bottom of the standard between the feet is generally of a triangular form. Extending rearwardly from the lower portion of the standard is an angled bar constituting the back support for the andiron.

I claim—

The ornamental design for an andiron as herein shown and described.

In testimony whereof I have hereunto set my hand in the presence of two subscribing witnesses.

THOMAS M. DUDGEON.
